UNITED STATES PATENT OFFICE

JOHANN FRIEDRICH SCHEID, OF HERMSDORF, GERMANY, ASSIGNOR TO HERMSDORF-SCHOMBURG-ISOLATOREN G. M. B. H., SITZ BERLIN, VERWALTUNG HERMSDORF IN THURINGEN

HIGH TENSION INSULATOR

Application filed October 18, 1924, Serial No. 744,324, and in Germany May 20, 1924.

My invention relates to high-tension insulators of the type in which several cups or petticoats are superposed to form a unit adapted to be attached to the usual supporting pin or bracket.

Double-cup or triple-cup insulators are known in which the interconnection between the single cups and the connection with the supporting bracket or pin is effected or ensured by way of cementing or baking and the like. This mode of uniting the parts together, however, is objectionable for the reason that the cups are liable to internal strains and tensions frequently resulting in premature destruction.

The object of my invention is to remedy this defect. With this object in view the present invention consists in the application of an elastic or resilient layer, preferably in the shape of a sleeve, intermediate between the single cups in order to give the assembled parts a firm and reliable but slightly yielding connection.

To this end the inner face of the outer cup or cups is shaped to form a thread whilst the opposed outer face of the inner cup or cups, either is roughened only or likewise threaded in a manner that the two meeting threads do not at all engage with each other or that they do engage with a certain play so as to afford a clearance for the reception of the said resilient layer or sleeve. The roughening of the outer face of the cups may be brought about by coarse sanding or knurling or by providing fine ridges in the surface or in any other appropriate manner.

Prior to the assemblage of the parts a layer of fibrous material such as hemp or hemp-hards, oakum, papier-maché, cardboard, paper mass or fibres or the like is applied to the outer roughened or threaded face of the inner cup or cups. Preferably the said layer is soaked in a liquid of preservative nature in order to obviate putrefaction and decay and, at the same time, of hardening properties in order to solidify with the said layer of fibrous material to form and constitute a yielding sleeve between the opposing faces of the parts. Liquids that suit the purpose best may be thick solutions of certain agglutinants,

such as dextrine, preferably mixed with a small percentage of any suitable preservative substance, such as carbolic acid, solutions of resinous substances, varnishes, tar, linseed oil mixed with minium or white lead and the like.

Having thus set forth in general the principles upon which my invention depends and having shown the particular improvements effected over the prior art, I shall now particularly describe two simple embodiments thereof which I have shown diagrammatically in the accompanying drawing forming a part of this specification, for the purpose of more fully disclosing my invention, but it is to be understood that such diagrams illustrate only two of the numerous possible embodiments of my invention which I have successfully used in practice and that I do not limit myself thereto in as much as many modifications may be devised by those skilled in the art without departing from the spirit of my invention.

In the drawing Figure 1 illustrates a triple-cup or triple-petticoat insulator adapted to be mounted on its supporting member, which may be a steel pin of conventional construction, the view being partly in section, partly in elevation, and Figure 2 is a similar view of a double-cup or double-petticoat insulator.

The insulator shown in Figure 1 comprises three cups 1, 2 and 3 of any suitable construction and assembled, as usually to form a unit. According to my invention the inner circumferential faces 2^a, 3^a of the two outer cups 2 and 3 are provided with a fine thread, whilst the opposed outer circumferential faces 1^b and 2^b of the cups 1 and 2 are provided with circumferential grooves 4 and the sections thereof intermediate between two adjacent grooves are roughened e. g. coarsely sanded, the inner and outer diametrical dimensions of the cups being such that, when assembled, a clearance will exist between each two opposed or cooperating surfaces of the cups for the entire area thereof. The clearance between the circumferential faces 1^b, 2^b and 2^a, 3^a, however, is, in accordance with my invention, occupied by or filled with resilient

matter of the kind herebefore indicated, such as hemp or similar fibrous mass, paper stuff and the like which will ensure a highly efficient connection between the parts. This 5 filler is applied to the outer roughened and peripherally grooved circumferential surface of the inner cup and the outer cup is then mounted thereon by a rotary movement causing the fine thread on the inner circumferential surface to bite into the material 10 applied to the inner cup and effect an embedding of the filler material into the peripheral grooves in the outer circumferential surface of the inner cup and embed the roughened circumferential surface of the inner cup 15 in the filler material, not only firmly uniting the cups and the cups to the support, but the filler material also compensating for variations in the cups effected by expansion and contraction of the material of the cups due to 20 atmospheric or other conditions.

In order to increase the firmness of the connection thus established the filling matter 25 may be soaked or treated with a suitable solidifying and preservative liquid, as above stated, acting to unite the fibrous material so as to form a solid but still yielding body in the shape of a sleeve between each two opposed faces of the cups and the supporting 30 member, respectively. In some cases the supporting bracket or pin may be screwed into the innermost cup as is usually done in insulators of usual construction.

In case that a fibrous mass of material such 35 as hemp, oakum and the like is employed for the filling purpose a binder of gelatin or viscous substance, such as varnish, a dextrine solution, a mixture of minium or white lead with boiled linseed oil and the like may be 40 used for the purpose of previously treating by soaking or saturating and uniting with said gelatine or viscous substance the fibrous material, but if a paper stuff or cardboard is employed tar appears to be preferable for 45 the purpose. Generally speaking, it is advisable to use, for the treating or soaking purpose, suitable substances or liquids of preservative nature or decay resisting properties in order to prevent the filler from decomposition and putrefaction.

In the embodiment shown in Figure 2 the 50 cups and the supporting pin are screw threaded and in order to assemble the same they must be screwed together. The threads, 55 however, differ in diametrical regards, so that a clearance or gap will exist between each two opposed faces which, however, is not wide enough to allow of disengaging the parts from each other in axial direction, it 60 being rather necessary to turn the one or the other in order to unscrew the same. In this modification there are two cups 6 and 7 only and, as will be clearly seen in the drawing, the coarse threads 8 of the cups and the pin 10, respectively, leave a clearance between

their opposed faces which is equal in width to the difference between the diameters of the outer thread of the one body and the diameters of the female thread of the engaging other body.

The clearance or free space between the threaded portions of the cups and the pin, respectively, is filled up with a fibrous material, such as hemp or oakum soaked and united with a solution of dextrine or of suitable resinous substances, linseed oil mixed with minium or the like or the filler may consist of cardboard treated or soaked with tar or the like. In the former case the soaked fibrous material is applied to the threaded faces in the usual manner of fixing insulators with hemp to the brackets or pins and the said material then soon solidifies to form a firm and yielding body or sleeve snugly fitting in the clearance or gap between the circumferential portions, the remaining portion of the gap being free and clear. In the latter case a small sheet of cardboard cut to conform in length and width to the threaded outer face of the cup 7 or the pin 10, is laid over and onto the said outer face of the cup or pin so as to form a closed sleeve 9 thereabout. As above stated the cardboard is treated or soaked with tar or the like and having been applied to the cup 7 or the pin 10 in the manner described, the cup 6 or the cup 7, respectively, is screwed over and about the sleeve 9 which owing to its flexibility, will adopt the threaded shape of the clearance or gap so as to lie snugly embedded within the latter and in intimate touch with the engaging faces of the cups or the pin, respectively.

In lieu of employing a sheet of cardboard a previously prepared closed sleeve of cardboard having the proper size to snugly fit to the threaded portion of the cup 7 or the pin 10, may be used. It goes without saying that the manner in which the parts are assembled and fixed with each other is the same in regard to the pin 10 and the cup 7 or the cup 7 and the outer cup 6. For electrostatic reasons the opposed or engaging faces of the cups and, if required, of the supporting pin may be covered with a conducting coating.

It will be evident that my invention, whilst still being adhered to in its main essentials, may be varied and adapted in many ways, as herein before stated already, according to the several requirements desired, or most suitable under different circumstances.

What I claim is:—

1. In an electric high tension insulator, an insulator cup having an outer recessed circumferential face, a sleeve of yielding material composed of massed fibers impregnated and united to each other by a gelatine and preservative binder surrounding the outer circumferential face of said cup and arranged in contact with said face and engaging the circumferential recesses and

thereby supported on the cup, and a second insulator cup surrounding said first-mentioned cup and having the inner circumferential face recessed and bearing upon said sleeve, said sleeve forming the sole means of securing said two cups.

2 In an electric high tension insulator, an insulator cup having an outer recessed circumferential face, a sleeve of yielding material composed of massed fibers impregnated and united to each other by a varnish surrounding the outer circumferential face of said cup and arranged in contact with said face and engaging the circumferential recesses thereby supported on the cup, and a second insulator cup surrounding said first-mentioned cup and having the inner circumferential face recessed and bearing upon said sleeve, said sleeve forming the sole means of securing said two cups.

3. An electric multipart insulator comprising a plurality of insulator cups arranged in nested relation and having opposed irregular faces secured to each other solely by an interposed elastic layer of massed fibers which are impregnated with and united to each other by varnish.

In witness whereof I have hereunto set my hand.

JOHANN FRIEDRICH SCHEID.
